UNITED STATES PATENT OFFICE

2,588,537

SMOKER'S APPLIANCE

Hugh Tennant Kelly, Wiseton,
Saskatchewan, Canada

Application June 20, 1949, Serial No. 100,177

1 Claim. (Cl. 131—237)

1

This invention relates to smoker's appliances such as ash trays and the like.

The provision of more convenient and satisfactory ash disposable receptacles for smokers has been the subject of much effort. Many types of such receptacles have heretofore been proposed but they are usually of expensive and complicated construction and are not entirely satisfactory to users.

An object of this invention is to provide an ash disposable receptacle of sturdy, compact, and inexpensive manufacture, and which includes means for readily collecting and concealing ashes, matches and other smokers' refuse. Another object is to provide an ash tray of the type referred to, wherein means are provided for extinguishing cigarettes, cigars and the like. Another object is to provide an ash tray of this type, which possesses few working parts and wherein all parts are readily replaceable, and which is conveniently operable to extinguish cigars or cigarettes and to dispose of ashes, stubs and the like.

The invention will be described with reference to the accompanying drawing, in which:

Fig. 1 is a plan view,

Fig. 2 is a side elevation, partly in section and
Fig. 3 is an end elevation.

In the drawing, 1 is a rectangular frame member having preferably an outwardly flared lip portion 2 on its upper edge. An ash receiving receptacle comprising an open, shallow, boxlike member or tray 25 telescopically and frictionally engages the lower edge portion of frame 1 for convenient removal from and replacement thereon. A plate or platform 3 is fixed to one end portion of frame 1 intermediate the top and bottom edges thereof. The plate 3 extends from side to side of the frame and terminates longitudinally of the frame on a transverse line approximately at the midsection of the frame. An upwardly extending flange 4 projects from the terminating edge of the plate 3, such flange carrying on its upper edge a plurality of cigar or cigarette receiving dished rests 5, such rests being disposed below the top of the frame 1.

A platform 6 is reciprocally mounted in the frame on side bars 7, such platform having its upper surface in sliding engagement with the lower surface of plate 3. The platform 6 has a generally rectangular ash or refuse supporting portion 9 and an end portion 11 in constant underlapping relation to plate 3. Springs 8 connected to the platform 6 and frame 1 normally maintain the platform 6 in the position shown in Fig. 1, i. e., with its portion 9 exposed in the end

portion of frame 1 beyond the terminating flange 4 of plate 3. Means for reciprocating the platform 6 against the action of springs 8 to slide the portion 9 underneath the plate 3 comprises an upright post 10 mounted on the portion 11 of platform 6. Post 10 extends through a longitudinally extending slot 12 in plate 3 and bears against the inner end of the slot in the normal position of platform 6 as shown in Fig. 1. A button 13 may be mounted on post 10 for ease of manual reciprocation thereof through slot 12.

Means for extinguishing burning cigars or cigarettes placed on portion 9 comprises a swinging plate or clapper 14 pivoted transversely of the frame 1 on pins 15 at a point adjacent the end edge of platform 6. A cog 16 is fixed to the outer end of one pin 15, such outer end being preferably square, as indicated in Fig. 2, to facilitate mounting of the cog thereon. A rack 18 is reciprocably mounted on the frame with its teeth in engagement with the cog 16. A rod 19 is fixed to the rack bar and has an inwardly extending end portion 20 projecting through a slot 21 in the frame 1. A spring 22 mounted on the rod 19 normally holds the portion 20 of the rod in engagement with one end of slot 21 and with a pivotable plate 14 resting on the lip portion 2. A button 23 may be mounted on portion 20 for manual reciprocation of the rod 19 and rack 18 against the action of spring 22. It will be observed that reciprocation of the rod 19 and rack 18 will rotate cog 16 and swing plate 14 down into overlying engagement with the portion 9 of the platform 6, as shown in dotted lines in Fig. 2. Thus, burning cigarettes or the like on portion 9 may be extinguished by pressure between plate 14 and portion 9. A button 24 may be provided on the outer face of plate 14 for manual engagement to apply additional pressure to the plate 14, if desired.

In use, ashes and other refuse are deposited on the portion 9 of the platform 6, and the plate 14 is pivoted counterclockwise about pin 15, as seen in Figure 2, to extinguish burning cigarettes and the like. Thereafter the platform 6 is reciprocated and the lower edge of the flange 4 of plate 3 acts as a scraper to remove the refuse on portion 9 and deposit it in the receptacle 25, which may be removed for emptying and cleaning as desired. Thus, the portion 9 of the platform 6 may be kept clean and neat in appearance at all times and danger from smouldering refuse is substantially eliminated. Nauseous odors are also substantially avoided and the need for manually extinguishing burning cigarettes and the like is

removed. Since the sides of the frame extend substantially above the cigar or cigarette rests 5, danger resulting from falling smouldering butts is removed. Moreover, immediate confinement of ashes and other refuse in the receptacle 25 prevents accidental scattering of such refuse and resultant untidiness.

The device is particularly useful when employed as an ash tray attachment in vehicles such as motor cars. Burning cigarettes may be conveniently tossed into the tray portion 9 and the buttons 13 and 23 actuated to dispose of the same. Thus, the eyes of the vehicle driver need only leave the road for a single glance, and the balance of the operation carried out by a touch of the hands. Accidents resulting from prolonged inattention to driving are thus avoided.

It will be observed that there are relatively few moving parts and that they are easily accessible for replacement when required.

The various parts may be constructed of any suitable materials, such as metal, plastic and the like.

I claim:

A smoker's appliance comprising a smoker's refuse-receiving tray, a frame removably carried by the tray, a planar platform having a smoker's refuse-receiving portion mounted in the frame, adapted to be reciprocated linearly in the plane of said platform, and surmounting the tray in substantially parallel relation thereabove, means for extinguishing cigarettes and for disposing of smokers' refuse deposited on said portion of the platform comprising pins rotatably mounted in the frame on an axis disposed parallel to and adjacent one edge of said portion, a plate hav-

ing one edge fixed to the pins and swingable on rotation of the pins, a spring-pressed member acting upon the plate and urging it away from said portion of the platform, and a manually engageable member connected to the pins for rotating the latter and swinging the plate into overlying relation to said portion of the platform to engage a lit cigarette therebetween, and means for sweeping the extinguished cigarette and smokers' refuse from said portion of the platform into said tray comprising a plate fixed in the frame in parallel relation to said platform and having an end portion overlying and contacting the upper surface of said platform, a scraping flange carried by said end portion, and a manually engageable handle fixed to the platform for reciprocating the platform in the frame.

HUGH TENNANT KELLY.
